MACHINE FOR MAKING SEPARABLE
FASTENER ELEMENTS

Edward J. Conlin, New Britain, Conn., assignor to
The G. E. Prentice Mfg. Co., New Britain, Conn.,
a corporation of Connecticut

Application December 7, 1939, Serial No. 307,975

20 Claims. (Cl. 140—71)

This invention relates to machines for use in the manufacture of slide fastener structures and has to do more particularly with machines for making separable fastener structures in which the fastener elements are the coils of a pair of spiral springs, one of such springs being a plain coiled spring while the other spring has a series of wave-like formations or hooks which are adapted to interlock with the coils of the plain spring to close the fastener structure. Machines for making fastener elements of this type are usually of a complicated nature necessitating an initial large investment for their installation and requiring the services of a skilled mechanic to keep them in order. Furthermore such machines have a relatively slow rate of production due to the fact that a material period of time is utilized in the cutting of the spirally shaped fastener members to the required length for use in the fastener structures in which they are to be incorporated.

The principal object of this invention is to provide an improved machine wherein fastener elements of the indicated type may be manufactured quickly and economically.

Another object of the invention is to provide a machine capable of forming fastener elements of the indicated type in a substantially continuous operation and of producing rapidly a large number of such elements in a predetermined size and in perfect condition.

A further object of the invention is to provide such a machine which will be relatively inexpensive to make and in which the parts will be relatively few in number, individually simple and rugged in construction and adapted in their assembled condition to be operated over long periods of time with freedom from mechanical difficulty.

Other objects and advantages of the invention as well as the novel features of construction, combination of elements and arrangement of the parts, will become apparent after a perusal of the following description read in connection with the accompanying drawings which illustrate an embodiment of the invention which is particularly adapted for manufacturing the fastener member provided with the wave-like formations or hooks and an embodiment of the invention which is particularly adapted for manufacturing the plain coiled spring fastening member to be associated with the hooked fastening member in the fastener structure.

In the drawings, Fig. 1 is a front elevational view of the machine which was designed particu-

larly to form the hooked spiral wire fastening member of the fastener structure; Fig. 2 is a right-hand side elevational view of the machine shown in Fig. 1; Fig. 3 is a front plan view of a slide fastener structure provided with spiral wire locking members of the type which the machines of this invention were designed to manufacture; Fig. 4 is a vertical sectional view illustrating more clearly the relation of the operating parts in the upper portion of the machine; Fig. 5 is an enlarged detailed side view of the upper portion of the machine looking from the left as viewed in Fig. 1; Fig. 6 is a vertical section of the mechanism for forming the hooked spiral wire, the section being taken along the line 6—6 of Fig. 7; Fig. 7 is an enlarged detailed plan view partly in section, of the mechanism for forming the hooked spiral wire; Fig. 8 is a top plan view of a wire illustrating the general sequence of operations performed thereon in the formation of the hooked spiral wire locking member; Fig. 9 is a side view of the wire shown in Fig. 8; Fig. 10 is a front elevational view of another embodiment of the invention designed particularly to form the looped spiral wire which is associated with the hooked spiral wire in the fastener structure; Fig. 11 is an enlarged detailed side view of the upper portion of the looped wire machine looking from the left as viewed in Fig. 10; Fig. 12 is an enlarged detail showing in vertical section the mechanism for feeding and forming the looped spiral wire; Fig. 13 is an enlarged detail in longitudinal section illustrating the arrangement of the parts for feeding the wire to the forming die and Fig. 14 is an enlarged detailed plan view of the mechanism for forming the looped spiral wire.

The disclosure of the invention will probably be facilitated by first generally referring to the construction of the article which is the product of the machines disclosed herein. This article, as can be seen from Fig. 3 of the drawings, comprises a pair of flexible tapes or stringers 1 and 2, to the opposed edges of which are attached a hooked spiral wire 3 and a plain spiral wire 4. The hooked spiral wire 3 is formed to provide a series of spirally arranged wave-like formations or hooks 5 which are adapted to interlock with the spirally arranged loops 6 of the plain wire 4 to close the fastener structure, as is shown in the lower portion of such figure. The interlocking of the members 3 and 4 is controlled by a slider 7 which is slidably mounted on such members and may be operated manually in one direction to cause interlocking engagement of the hooks 5

with the loops 6 and in the other direction to disengage such hooks and loops to open the fastener structure.

Turning now to the machine illustrated in Figs. 1 to 7 of the drawings, which, as has been previously mentioned, was designed particularly to make the hooked spiral wire 3, there is provided a table 10 which is supported on a pair of side frame members 11 and 12. Beneath the table 10 there is positioned the main shaft 15 of the machine which is rotatably supported at one end by a bearing block 13 mounted on the side frame member 11 and rotatably supported adjacent its other end by a bearing block 14 provided on the side frame member 12. The end of the shaft 15, extending through the bearing block 14, is provided with a pulley 16 on which is mounted a belt 17 which connects such pulley to a pulley 18 mounted on the end of a motor shaft 19. The motor 20 is supported on the side frame member 12 in any suitable manner and means (not shown) are also provided to connect such motor 20 to a source of current and to control the operation thereof.

Means are provided for transmitting the rotative movement of the shaft 15 to the various operating mechanisms utilized in the manufacture of the hooked spiral wire member of the fastener structure, such means including a clutch member 21 which is connected to the shaft 15 by means of a key 22 to enable it to partake of the rotative movement of the shaft while yet enabling it to be shifted longitudinally with respect to such shaft, as is shown more clearly in Fig. 4 of the drawings. The clutch member 21 is provided with friction material 23 which engages with friction material provided on the opposed face of a clutch plate 24 rotatably mounted on the shaft 15. The clutch member 21 is normally maintained in driving relation with the clutch plate 24 by means of a compression spring 25 which encircles the shaft 15 and bears at one end against the clutch member 21 and at its other end against a sprocket wheel 26 affixed to the shaft 15. Connected to the clutch plate 24, as by means of a plurality of horizontally disposed bolts 28, is a bevel gear 27 whose interior surfaces in part bear against a collar provided on the clutch plate 24 and in part are rotatably supported on the reduced end of an aligning or bearing collar 29 mounted on the shaft 15. The coaxing positions of the clutch plate 24, bevel gear 27, and bearing collar 29 are maintained by means of a collar 30 positioned adjacent to the bearing collar 29 and affixed to the shaft 15 and a bushing 31 positioned intermediate the clutch members 21 and 24 and secured to the shaft 15 in any suitable manner such as by a set screw. The gear 27 meshes with a bevel gear 32 which is mounted on the lower end of a depending shaft 33, the latter of which extends upwardly through the horizontally disposed arms of a roller bracket 35. Intermediate the arms of the bracket 35 and fixedly secured to the shaft 33, is a roller 34 which is provided at its lower end with a spur gear 36 adapted to mesh with a spur gear 37 provided on the lower end of a roller 38. The roller 38 is mounted on a vertically disposed shaft 39 whose ends extend through apertures in the spaced arms of a roller bracket 40 which is positioned adjacent to the roller bracket 35 and connected thereto by means of a horizontally disposed plate 39 (see Fig. 7). Provided on the upper end of the roller 34 is a kinking gear 41 which cooperates with a kinking gear 42, provided on the upper end of the roller 38 to pro-

duce the wave-like formations in the wire member 3 of the fastener structure prior to forming it into spiral form, as will be hereinafter more fully explained.

It will be seen from the foregoing that the rotative movement of the shaft 15 will be transmitted to the kinking gears 41 and 42 through the clutch mechanism described, the bevel gears 27 and 32, shaft 33 and spur gears 36 and 37 provided on the rollers 34 and 38. It will also appear that such rotative movement can be made intermittent by a proper operation and control of the clutch mechanism as will hereinafter be more fully explained. The rotative movement of the shaft 15 is also transmitted to a shaft 47 (see Figs. 1 and 4) which is rotatably supported on a pair of spaced standards 48 and 49. The shafts 15 and 47 are connected by a chain 45 which is supported at one end on the sprocket wheel 26 mounted on the shaft 15 and is supported at its other end by a sprocket wheel 46 provided on the right-hand end of the shaft 47, as viewed in Fig. 1 of the drawings. Intermediate the bearing standards 48 and 49 there is provided on the shaft 47, a sprocket wheel 50 (see Figs. 1 and 2) which carries a chain 51, the lower end of such chain passing around an idler sprocket wheel 52. The idler wheel 52 is rotatably mounted on an axle member 53 which is provided at one end with a hand wheel 54 and at its other end extends through a chain-adjusting channel 56 and a clamp 55, the shank of such member being threaded and being in threaded engagement with the clamp 55. Thus by operating the handwheel 54, the sprocket wheel 52 may be adjusted from the position shown in Fig. 1 to the position shown in Fig. 2 or any other position desired to take care of varying lengths of fasteners, as will hereinafter become more clear. The chain adjusting channel 56 is suitably supported at its upper end to the underside of the table 10 and braced at its lower end by means of a brace 57 which is attached to the side frame member 11 as is shown more clearly in Fig. 1 of the drawings.

The chain 51 is provided at spaced intervals with a plurality of trip or knocker links 58 which are formed to interengage with a knocker plate 59 in the movements of the chain around the sprocket wheel 50. As is shown more clearly in Fig. 5 of the drawings, the knocker plate 59 is mounted on the rear end of a rocker arm 60 which is pivotally mounted adjacent its forward end on a pin 61 fixedly secured to the roller bracket 35 (compare Fig. 4). The rocker arm 60 normally rests on a stop member 61 provided on the table of the machine, as is shown in full lines in Fig. 5 of the drawings, but may be lifted about the pin 61 by the engagement of a knocker link 58 with the knocker plate 59 to the position shown in dotted outline in such figure. The forward end of the rocker arm 60 is fork-shaped, the lower arm 62 of the fork being in engagement with the upper end of a shifting arm or rod 63 which extends downwardly through an aperture in the table 10 and at its lower end is provided with a swivel block 64 (see Figs. 1 and 2). Pivotally connected at one end to the swivel block 64 is an arm 65 which is pivotally connected at its other end to a bracket 66 mounted on the side frame member 11 of the machine. Also connected to the swivel block 64 is one end of a link 67 which is connected at its other end to the lower end of a shifting or clutch lever 68, the latter of which is pivotally connected at its other end to a bracket 69 attached to the under surface of the table 10.

The clutch lever 68 is divided adjacent its upper end to form a clutch fork or strap 70 (see Figs. 1, 2 and 4) provided with means for engaging a groove in the clutch member 21.

The upper arm 71 of the forked end of the rocker arm 60 is provided with a knife or blade 72 whose cutting edge moves or wipes across the exit end of a passageway 101 provided in a cutting die 102 (see Figs. 1 and 7) when the rocker arm 60 is lifted by the engagement of a knocker link 58 with the knocker plate 59.

It will be evident from the foregoing description of the mechanism associated with the shaft 47, that as the sprocket wheel 50 is rotated by the shaft 15, through sprocket wheel 26, chain 45, sprocket wheel 46 and shaft 47, the chain 51 will be moved in a clockwise direction, as viewed in Fig. 5 of the drawings. As each of the trip or knocker links 58 of the chain 51 comes into engagement with the lower end of the knocker plate 59, the latter, together with the rocker arm 60 will be pivoted upwardly about the pin 61, thereby depressing or lowering the forked arms 62 and 71 at the forward end of the rocker arm 60. The lowering of the arm 71 causes the blade 72 to wipe across the exit end of the passageway 101 while the simultaneous lowering of the arm 62 causes the shifting rod 63 to be lowered, thereby causing the shifting lever 68 through the swivel block 64 and the link 67 to pivot about its pin support 69 to move the clutch member 21 away from the clutch plate 24. As a result of this operation the bevel gears 27 and 32 and consequently the kinking gears 41 and 42 are disengaged from their driving relation with the shaft 15. In order that the rotative movement of the kinking gears 41 and 42 may be stopped as soon as the clutch member 21 is disengaged from the clutch plate 24, a brake 82 (see Fig. 4) is brought into engagement with the clutch member 24 to prevent it from overrunning after its disengagement from the clutch member 21. The brake 82 is carried by a brake arm 73 which is pivotally supported at its rear end to a swivel bracket 74 attached to the under surface of the table 10, as is shown more clearly in Figs. 1 and 2 of the drawings, and is connected at its forward end by means of a link 75 to a brake arm lever 76, the latter of which is secured at one end to the side frame member 12 and at its other end is provided with an opening through which the shifting arm or rod 63 extends. The apertured end of the brake arm lever 76 is normally maintained against a shoulder 78 formed on the shifting rod 63 by means of a coiled spring 80 which surrounds the rod 63 and whose upper end is seated against a shoulder 79 provided in spaced relation above the shoulder 78. Thus, as soon as the shifting arm 63 is depressed as a result of the pivotal actions of the knocker plate 59 and rocker arm 60, the brake arm lever 76 is pressed down by the resilient connection of the spring 80 to such arm 63 and in turn through the link 75 causes the brake arm 73 to be pivoted downwardly to bring the brake shoe 82 carried thereby into engagement with the clutch plate 24. The clutch plate 24 and consequently the kinking gears 41 and 42 are therefore immediately stopped in their rotative movements as soon as the clutch disengages the driving action of the shaft 15 from such kinking gears. It will thus be seen that the kinking gears rotate intermittently for a period depending upon the spaces between the trip links 58 and that as soon as such links cause the actuation of the clutch mechanism, braking means are immediately called into

operation to stop the rotative movement of such gears.

The kinking gears 41 and 42 have a twofold purpose in the operation of the machine. In the first place they impart to the wire a sinuous configuration in one plane and in the second place they function as feed rolls to feed the kinked wire to the spiral-forming die. The wire to be kinked may be fed from a coil or roll which may be carried on a supporting plate or table provided at the rear of the machine or otherwise suitably disposed with relation to the machine. The wire 85 is passed forwardly in its feed to the kinking gears through a guide 88 which is carried by the plate 89 connecting the roller brackets 35 and 40 and adapted to direct such wire between the kinking gears 41 and 42, as is shown more clearly in Figs. 6 and 7 of the drawings. During its passage between the kinking gears 41 and 42, the wire is given a wave-like formation, the distorted wire being then passed to a die member adapted to give it a spiral form. The several operations which are performed on the wire can best be seen from the showing in Figs. 8 and 9 of the drawings. Referring to such figures, the straight portion of the wire which has been subjected to the action of the kinking rollers 41 and 42 is indicated by the reference character 85 while that portion of the wire which has been subjected to the action of the kinking rollers but has not as yet been formed into a spiral form is indicated by the reference character 90. It will be noted from these figures that as a result of the kinking operation the wire is deformed in one plane only, such plane being parallel to the horizontal surfaces of the table and the wire is given a sinuous form. The kinked portion 90 of the wire is then bent at right angles to the plane of the wave-like formations and at the same time is formed into a spiral wire of such diameter that each spiral thereof includes three complete kinks or waves, the kinks or waves of each spiral being aligned in rows with the kinks or waves of the other spirals to form a longitudinal series of hooks 5 which are positioned in spaced relation about the periphery of the formed spiral wire as is clearly illustrated in Figs. 3, 8 and 9 of the drawings. Thus there are three series of hooks 5 on the fastening member 3 by which it may be interlocked with the loops of the plain spiral wire 4. Referring back to Figs. 6 and 7 of the drawings, the kinked portion 90 of the wire, which emerges from the kinking gears 41 and 42 is fed by the latter through a suitable guide 91 which is secured at its forward end to a block 92, mounted on a clamp 93 which is supported in any suitable manner on a die bed 94 carried by the table 10. Positioned in cooperative relation with the forward end of the guide 91 is a die 95 provided with a channel or elongated opening 96 through which extends the die member 97. The die member 97 may be adjusted longitudinally in the die 95 and is maintained in its adjusted position by means of a set screw 98. The portion 99 of the die member which lies in the path of the exit or forward end of the guide 91 is tapered in form to control the diameter of the spiral coil to be formed and is provided with a spiral thread. As the kinked portion 90 of the wire is fed to the portion 99 of the die member under the influence of the kinking gears 41 and 42, it is forced around such portion by the action of the adjacent interior surface portions of the channel 96 and given a spiral form, the tapered spiral portion 99 directing the spiralled wire towards the reduced end portion 100.

of the die member 97. After passing from the die 95, the spiralled wire enters the aligned passageway 101 of a cutting die 102 and, as it emerges from such passageway, is cut to the desired length by the intermittent operation of the blade 72, as has been previously explained.

It will be evident from the foregoing description of the machine for forming the hooked spiral wire that it is composed of parts which are relatively simple and rugged in construction and will be relatively inexpensive to make. The machine in its operations produces the desired fastener elements quite rapidly, the wire being fed and formed into hooked spiral form in a continuous manner except for the intermittent interruptions in the feed to enable the formed wire to be cut to the proper length. The interruptions in the feed of the wire are only momentary in nature and do not continue for an appreciable period as have the interruptions in prior machines for cutting spiral-formed wire. The wire, as has been previously described, is fed forwardly from a coil or roll to the forming die 95 by the kinking gears 41 and 42 which are driven from the main shaft 15 of the machine through the clutch members 21 and 24, beveled gears 27 and 32, shaft 33 and spur gears 36 and 37 provided on the rollers 34 and 38. The wire fed by the kinking gears enters the die 95 through an aperture aligned with the guide 91 and passes into the passageway 96 of the forming die where it is forced around the portion 99 of the die member 97 by the feed of the kinking gears and the action of the adjacent interior surface portions of the channel or passageway 96 and given a spiral form, the tapered spiral portion 99 of the die member directing the spiral wire towards the reduced end portion 100 of the die member 97 and out of the die. After passing from the die 95 the spiral wire enters the aligned passageway 101 of the spaced cutting die 102 and as it emerges from such passageway the spiral wire is cut to the desired lengths by the intermittently operating blade 72 which is mounted at the forward end of the rocker arm 60. The means for imparting intermittent operation to the blade 72 and rocker arm 60 includes the sprocket wheel 26 mounted on shaft 15, chain 45 and sprocket wheel 46 which transfer the rotative movements of the shaft 15 to the shaft 47 and a sprocket wheel 50 mounted on such shaft. The rotation of sprocket wheel 50 causes the knocker links 58 on chain 51 to intermittently come into engagement with and to raise the inner end of the rocker arm 60. The sharp blow imparted to the inner end of the rocker arm 60 by a link 58 depresses the forward end of such arm and causes the blade mounted on the latter to wipe past the aperture 101 in the cutting die 102 and thereby sever the length of coiled spring extending from such die. At the same time the rod 63 mounted on the forked portion 62 of the forward end of the rocker arm 60 is depressed to move the block 64 downwardly thereby causing the pivoted arm 68 through the link 67 to move the clutch member 21 out of engagement with the clutch member 24 thereby breaking the driving connection between the shaft 15 and the kinking gears 41 and 42. On the return of the rocker arm 60 to its normal at rest position, the clutch mechanism again becomes operative to again cause the kinking gears 41 and 42 to resume their feed of the wire to the coiling mechanism and likewise to the cutting die 102. These series of operations are repeated every time a link 58 of the continuously driven chain 51 comes into engagement with the inner

end of rocker arm 60 and strikes the latter out of its path.

The embodiment of the invention illustrated in Figs. 10 to 14, like the machine hereinabove described, includes a table 10' provided with side frame members 11' and 12', on the latter of which is supported an electric motor 20'. Like the previously described embodiment also, this machine includes a pulley wheel 18' attached to the motor shaft 19' and connected to a driven pulley wheel 16' on the main drive shaft 15' of the machine by means of a belt 17', whereby rotative movement is imparted to the shaft 15'. Also the rotative movement of the shaft 15' is transmitted to a sprocket wheel 58' through a sprocket wheel 26' mounted on shaft 15', chain 45', sprocket wheel 46', and shaft 47', the latter of which is rotatably mounted on bearing standards 48' and 49' and carries the sprocket wheel 50'. This machine is also similar to the previously described embodiment, in that the rotative movement transmitted to the sprocket wheel 50' is utilized to drive a chain 51' which at its lower end is connected to an idler sprocket wheel 52' adjustably mounted on the chain-adjusting channel 56' which is attached at its upper end to the under side of the table 10' and is made rigid against sidewise movement by the brace 57' connecting its lower end to the side frame member 11'. Chain 51', like chain 51, includes a plurality of spaced trip or knocker links 58' adapted to come into engagement with a knocker plate 59' mounted on the rear end of a rocker arm 60' which is pivotally mounted adjacent its forward end and normally rests on a stop arm 81' provided on the table 10' of the machine, as is shown more clearly in Fig. 11 of the drawings. As in the first embodiment, the raising of the knocker plate 59' and rocker arm 60' causes a knife blade 72' provided on the forwardly projecting end 71' of the rocker arm 60' to wipe across the exit end of a passageway 101' provided in a cutting die 102'.

It will be apparent from the foregoing that this embodiment of the invention is similar to the previously described embodiment in that the rotative movements of the main shaft are utilized to drive a chain provided with trip links to actuate a rocker arm on the forward end of which is provided a blade adapted to cooperate with the cutting die to cut off predetermined lengths of the spiral wire formed by the machine. This embodiment differs from the previously described machine however, in that the rocker arm assembly does not control clutch mechanism for intermittently disconnecting a set of kinking gears from the main shaft and simultaneously braking the rotative movements of such kinking gears to bring them to rest as soon as they are disconnected from the driving action of the main shaft.

The means for feeding the wire to the forming members and for interrupting the feed of the wire during the cutting operation in this embodiment of the invention is shown more clearly in Figs. 10, 12 and 13 of the drawings. These means include the main shaft 15' which is rotatably supported on the bearing standards 49' and 110 above the table 10' and is provided with a reduced portion 111 which extends through aligned bearing apertures provided in a pair of spaced standards 112 and 113. The outer projecting terminal end of the shaft portion 111 extends through the hub like portion 114 of rocker arm 60' which is rotatably supported thereon and which is provided with a cam member 115 (see Figs. 11 and 13). Mounted on the shaft portion 111, intermediate

the standards 112 and 113, is a roller 116 which is reduced in cross sectional dimensions adjacent to the standard 113. The roller 116 is secured to the shaft portion 111 as by means of a set screw and carries on its reduced end portion a set of spur gear teeth 117. Meshing with the spur gear teeth 117 are spur gear teeth 118 provided on the reduced end of a roller 119 which overlies the roller 116. The roller 119 is fixed to a floating pin 120 which extends through vertical slots 121 and 122 provided in the standards 112 and 113, respectively, and carries on its outer end a cam roller 123 which engages with the cam member 115. Normally the cam roller 123 and the cam member 115 are in the positions shown in Fig. 11 of the drawings with the roller 123 fully seated on the arcuately shaped surface of the member 115. When the rocker arm 60', however, is thrown upwardly about the shaft portion 111 as a pivot the cam member 115 causes the cam roller 123 to be lifted, thereby tilting the floating pin 120 about one end, as is shown in Fig. 13 of the drawings. In the normal condition of the cam roller 123 and the cam member 115, the enlarged portion of the roller 119 is maintained in engagement with the enlarged portion of the roller 116 by means of a pair of spring pressed blocks 124 and 125 which are slidably mounted in the vertical slots 121 and 122, respectively. As is shown more clearly in Fig. 13 of the drawings, the slide block 125 is provided with an aperture through which the head end of the pin 120 extends, such block being maintained in position in its associated slot 122 by means of the head 126 of the pin 120 and the reduced end of the roller 119. Seated on the upper end of the block 125 is a coiled spring 127 which at its upper end engages a spring seat 128 provided on the undersurface of a cross plate 129 spanning the upper ends of the standards 112 and 113 and being fixedly attached thereto. The block 124 is positioned in the slot 121 intermediate the roller 119 and the cam roller 123 and is provided with an arcuately shaped bottom surface which bears on the portion of the pin 120 which extends through the slot 121. The block 124 is maintained in engagement with the pin 120 by means of a vertically disposed coiled spring 130 whose upper end engages a spring seat 131 provided on the adjacent end of the cross plate 129.

It will become evident from the foregoing description of the feeding and feed interrupting means that the rotational movement imparted to the roller 116 by the shaft 15' is utilized through the gear teeth 117 and 118 to rotate the roller 119, the latter of which is normally pressed into engagement with the roller 116 by the action of the spring pressed blocks 124 and 125 on the pin 120. The rollers 116 and 119 are thus enabled to function as a means for feeding the wire to the mechanism for forming it into a spiral spring. As the chain 51' travels, the trip or knocker links 58' thereof are periodically brought into engagement with the knocker plate 59' thereby intermittently lifting the rocker shaft 60' and causing the cam member 115 on the hub-like portion 114 thereof to intermittently lift cam roller 123 on the end of pin 120 against the pressure of the spring pressed blocks 124 and 125 to tilt the pin a sufficient amount to break or to stop the frictional feed of the wire by the rollers 116 and 119 without, however, disengaging the spur gears 117 and 118, as is shown in Fig. 13 of the drawings. As soon as the normal conditions of the cam member 115 and roller 123 are again restored with the assistance of the pressure of the spring pressed blocks

124 and 125 the floating pin 120 will again be in a position to bring the rollers 116 and 119 into a condition where they can again frictionally engage the wire to feed it forwardly to the spiral forming mechanism.

The wire is passed from a source of supply at the rear of the machine to the feed rollers 116 and 119 through a guide 132 which is mounted on a plate 133 secured to the rear surfaces of the standard 124, as is shown more clearly in Fig. 12 of the drawings. After the wire has passed the feed rollers 116 and 119, it enters into a guide 134 (see Figs. 12 and 14) which delivers the wire to the spiral forming mechanism consisting of a die member 135 and a cooperating die wheel 136. The die member 135 is an elongated cylindrically shaped piece of metal which extends through a passageway in a cylindrically shaped block 137 and is adjustably secured to said block as by means of a set screw 138. The cylindrical block 137 is positioned in a longitudinal aperture provided in a supporting block 139 and is adjustably secured in place by means of a set screw 140. The die wheel 136 is revolvably mounted on the rear end of a supporting arm 141 which extends through a transverse passage in a cylindrically shaped block 142 and is adjustably secured thereto as by means of a set screw 143. The block 142, like the block 137, extends through an opening in the supporting block 139 and is adjustably secured in position as by means of a set screw 144.

The end of the die member 135 disposed in front of the guide 134 is reduced in cross-sectional area to provide a tapered portion 145 over which the wire is directed by the guide 134 into the space formed between such portion and the concaved face provided on the periphery of the die pulley 136 as will be seen from Fig. 14 of the drawings. As the wire passes between the tapered portion 145 of the die member 135 and the concaved face of the freely rotating pulley 136 it is bent into a spiral shape. As the wire is bent it enters into spiral-shaped spaces formed by the spiral thread 146 provided on the outer end portion of the die member 135 adjacent to the forming surface portion 145 thereof which operates to correctly space the coils of the spiral wire and to feed the formed spiral wire, under the feeding force of the rollers 116 and 119, into the passageway 101' of the cutting die 102'. As the formed spiral wire emerges from the cutting die 102', it is cut into predetermined lengths by the action of the cutting blade 72' under the influence of the tripping links 58', knocker plate 59' and rocker arm 60', as has been previously explained. The feed of the feeding rollers 116 and 119 is momentarily disrupted during these cutting operations as has also been pointed out.

While I have hereinabove described and illustrated in the drawings specific embodiments of my invention, it will be obvious to those skilled in the art that various other changes in the particular construction and arrangement of the several parts may be made without departing from the invention.

I claim:

1. In a machine for making fastener elements, the combination of means for producing a series of wave-like formations in a wire and for feeding the wire forwardly through forming mechanism and to cutting means, mechanism including a stationary die member associated with said feeding means for forming the waved wire fed therefrom around said die member and into a coiled spiral shape and adapted to direct the coiled wire

in a direction transverse to the line of feed of the waved wire, cutting means spaced from said spiral forming mechanism, means for actuating said cutting means at predetermined intervals to cut the coiled wire into predetermined lengths and means for rendering said first mentioned means momentarily inoperative to deform and feed the wire during the cutting operation.

2. In a machine for making fastener elements, the combination of a revolvable shaft, a pair of kinking gears driven by said shaft and adapted to produce a series of wave-like formations in a wire and to feed the wire forwardly through forming mechanism and to cutting means, mechanism including a stationary die member associated with said kinking gears for forming the waved wire fed therefrom around said die member and into a coiled spiral shape and adapted to direct the coiled wire in a direction transverse to the line of feed of the waved wire, cutting means spaced from said spiral forming mechanism and including a pivoted member bearing a cutting blade, means for actuating said pivoted member at predetermined intervals to cause the cutting blade to cut the coiled wire into predetermined lengths and means controlled by said pivoted member for rendering said kinking gears momentarily inoperative to deform and feed the wire during the cutting operation.

3. In a machine for making fastener elements, the combination of a revolvable shaft, a pair of revolvably mounted kinking gears arranged to produce a series of wave-like formations in a wire and to feed the waved wire, means connecting one of said kinking gears in driven relation to said revolvable shaft and in driving relation to the other of said kinking gears, mechanism associated with said kinking gears for forming the waved wire fed therefrom into a coiled spiral shape, cutting means associated with said spiral forming mechanism, means for actuating said cutting means at predetermined intervals to cut the coiled wire into predetermined lengths and means controlled by said actuating means for momentarily breaking the driven relation of said first-mentioned kinking gear with said revolvable shaft during the cutting action of said cutting means whereby said kinking gears are rendered inoperative to deform and feed the wire during the cutting operation.

4. The combination of a revolvable shaft, a pair of revolvable means driven by said shaft and adapted to continuously feed a wire forwardly through forming mechanism and to cutting means, mechanism including a stationary die member for forming the wire fed by said revolvable means around said die member and into a spiral form, cutting means associated with said spiral forming mechanism and spaced therefrom, means for actuating said cutting means at predetermined intervals to cut the coiled wire into predetermined lengths, and means intermediate said revolvable means and said actuating means and operable by the latter to momentarily disconnect said revolvable means from its driven relation with said shaft and thereby render it inoperative to feed the wire during the cutting operation.

5. The combination of a revolvable shaft, means driven by a shaft for feeding a wire through forming mechanism and to cutting means, mechanism including a stationary die member for forming the wire fed by said feeding means around said die member and into a spiral form, cutting means associated with said spiral

forming mechanism including a pivoted arm, a cutting blade carried by said arm, means for striking said arm at predetermined intervals to cause said blade to cut the coiled wire into predetermined lengths, and feed control means connecting said pivoted arm with said feeding means and actuatable by said arm in its pivotal movements to momentarily interrupt the feed of said feeding means during the cutting stroke of said blade.

6. The combination of a revolvable shaft, means driven by said shaft for feeding a wire through forming mechanism and to cutting means, mechanism including a stationary die member for forming the wire fed by said feeding means around said die member and into a spiral form, cutting means associated with said spiral forming mechanism including a pivoted arm, a blade carried by said arm, a constantly rotating chain driven by said revolvable shaft, a plurality of trip links provided on said chain and adapted to strike said pivoted arm at predetermined intervals to cause said blade to cut the coiled wire into predetermined lengths, and feed control means carried by said arm and operatively connected to said feeding means, said feed control means being operative on each pivotal movement of said arm caused by said trip links to momentarily interrupt the feed of said feeding means during the cutting stroke of said blade.

7. The combination of a revolvable shaft, means for feeding a wire driven by said shaft, mechanism for forming the wire fed by said feeding means into a spiral form, cutting means associated with said spiral forming mechanism including a cutting die, an arm pivoted intermediate its ends, a knocker plate mounted on one end of said arm and a cutting blade mounted on the other end thereof and being operatively associated with said cutting die, a constantly rotating chain driven by said revolvable shaft and carrying a plurality of trip links adapted to engage said knocker plate at predetermined intervals to cause said blade to coat with said die to cut the coiled wire into predetermined lengths, and means for momentarily interrupting the feed of said feeding means during the cutting stroke of said blade.

8. The combination of a revolvable shaft, means driven by said shaft for feeding a wire through forming mechanism and to cutting means, mechanism including a stationary die member for forming the wire fed by said feeding means around said die member and into a spiral form, cutting means associated with said spiral forming mechanism including a pivoted arm, a cutting blade carried by said arm, means for striking said arm at predetermined intervals to cause said blade to cut the coiled wire into predetermined lengths and means controlled by said pivoted arm for rendering said feeding means momentarily inoperative to feed the wire during the cutting stroke of said blade.

9. The combination of a revolvable shaft, means for feeding a wire driven by said shaft, clutch mechanism intermediate said shaft and feeding means, mechanism for forming the wire fed by said feeding means into a spiral form, a cutting means associated with said spiral forming mechanism, means for actuating said cutting means at predetermined intervals to cut the coiled wire into predetermined lengths, and means controlled by said actuating means for operating said clutch mechanism to disengage

said feeding means from their driven relation with said shaft during the cutting operation.

10. The combination of a revolvable shaft, means for feeding a wire driven by said shaft, clutch mechanism intermediate said shaft and feeding means, mechanism for forming the wire fed by said feeding means into a spiral form, a cutting die adapted to receive the spirally formed wire, a pivoted arm, a knife carried by said arm adapted to coact with said cutting die to sever the spiral wire, tripping means adapted to actuate said pivoted arm at predetermined intervals to cause said arm to make a cutting stroke and means connecting said pivoted arm with said clutch mechanism and adapted to render the latter inoperative to impart the driving action of said shaft to said feeding means every time said pivoted arm is actuated to cause said knife to make a cutting stroke.

11. The combination defined in claim 10 in which said connecting means comprises an actuating rod connected to said pivoted arm and movable by the latter, and a clutch lever connected with said clutch mechanism and said actuating rod and adapted to disengage said clutch mechanism every time it is actuated by said rod during the cutting stroke of the knife.

12. The combination of a revolvable shaft, means for feeding a wire driven by said shaft, mechanism including a stationary die member for forming the wire fed by said feeding means around said die member and into a spiral form, cutting means spaced from said spiral forming mechanism, means for actuating said cutting means at predetermined intervals to cut the spiral wire into predetermined lengths, means intermediate said shaft and said actuating means and controlled by the latter, said last-mentioned means being operable on operation of said actuating means to break the driving relation of said feeding means with said shaft and thereby render said feeding means inoperative to feed the wire during the cutting operation and stopping the rotative movements of such feeding means during such period.

13. The combination defined in claim 9 in which is included a brake adapted to engage with a rotating member of said clutch mechanism, and means connecting said brake with said actuating means and adapted to press said brake into engagement with the rotating clutch member when said actuating means operates to render said clutch mechanism inoperative.

14. The combination of a revolvable shaft, means for feeding a wire driven by said shaft, a die member extending transversely to the path of feed of the wire and comprising a tapered section provided with a spiral thread, a die surface surrounding said tapered section and adapted to coact with the latter to form the wire into a spiral shape, means for guiding the wire intermediate said tapered section and said die surface, cutting means associated with said spiral forming means, means for actuating said cutting means at predetermined intervals to cut the spiral wire into predetermined lengths, and means for momentarily interrupting the feed of said feeding means during the cutting operation.

15. The combination of a revolvable shaft, means for feeding a wire driven by said shaft, a die block having a passageway extending transversely to the path of feed of the wire, a die member positioned in such passageway and having a tapered portion provided with a spiral thread and adapted to coact with the adjacent

interior surfaces of the passageway to form the wire into a spiral shape and to feed the shaped wire in a direction at right angles to the direction of feed of said feeding means, means for guiding the wire from said feeding means to said die block, a cutting die adapted to receive the wire fed from said die block, a pivoted knife associated with said cutting die, means for actuating said knife at predetermined intervals to cause said knife and cutting die to cut the spiral wire into predetermined lengths, and means controlled by said actuating means for momentarily interrupting the feed of said feeding means during the cutting stroke of said knife.

16. The combination of a revolvable shaft, a feed roller mounted on said shaft, a floating roller associated with said feed roller, yieldable means normally maintaining said floating roller in position with respect to said feed roller to enable said rollers to feed a wire, means drivingly connecting said floating roller to said shaft, a cam member connected to said floating roller, a cam member on said shaft adapted to coact with the cam member of said floating roller to withdraw said floating roller from operative association with said feed roller against the pressure of said yieldable means, mechanism for forming a wire fed by said feed and floating rollers into a spiral form, cutting means associated with said spiral forming mechanism, and means for actuating said cutting means when said cam members have rendered the feed and floating rollers inoperative to feed the wire.

17. The combination called for in claim 16 in which each of said rollers is provided at one end with a set of gear teeth engaged in driving connection with the set of gear teeth of the other roller and said cam members are positioned adjacent to the other ends of said rollers, whereby said floating roller is tilted by said cam members to render such rollers inoperative to feed the wire without disengaging the sets of gear teeth at the other ends of said rollers.

18. The combination of a revolvable shaft, means for feeding a wire driven by said shaft, a die member extending transversely to the path of feed of the wire and comprising a fixed wire shaping surface, a freely revolving die wheel associated with said surface and adapted to coact with the latter to bend the wire fed by said feeding means, means for guiding the wire intermediate said shaping surface and said die wheel, said die member being provided adjacent to said surface with a spiral groove adapted to receive the bent wire and form the same into the proper spiral shape, cutting means associated with said die member, means for actuating said cutting means at predetermined intervals to cut the spiral wire into predetermined lengths, and means for momentarily interrupting the feed of said feeding means during the cutting operation.

19. The combination of a revolvable shaft, a feed roller mounted on said shaft, a floating roller associated with said feed roller, yieldable means normally maintaining said floating roller in position with respect to said feed roller to enable said rollers to feed a wire, a cam member connected to said floating roller, a second cam member on said shaft adapted to engage with said first cam member, a pivoted arm connected to said second cam member, a cutting blade carried by said cam and means for striking said arm at predetermined intervals to cause said blade to be actuated and to cause said second cam member to actuate said first cam member

to disrupt the feed of said feed and floating rollers.

20. The combination of a revolvable shaft, a pair of revolvable means driven by said shaft and adapted to feed a wire through forming mechanism and to cutting means, mechanism including a stationary die member for guiding the wire feed by said feeding means around said die member and forming it into a spiral form, said mechanism delivering the coiled wire in a direction transverse to the line of feed of said revolvable means, a cutting die spaced from said forming mechanism and having a die hole positioned in substantial alignment with the line of feed of the coiled wire from said forming mecha-

nism, a cutting means including a blade arranged to wipe across the exit end of the die hole in said cutting die and having a position of rest, and actuating means for causing said blade to wipe past the die hole from its position of rest, at predetermined intervals, said actuating means including a member mounted for pivotal movement, means operatively connecting said blade to said member, a constantly rotatable chain driven by said revolvable shaft and a trip link provided on said chain and adapted to strike said pivotal member at predetermined intervals to cause said blade to move in its cutting stroke past the die hole in said cutting die.

EDWARD J. CONLIN.
